UNITED STATES PATENT OFFICE

2,484,219

DETACHABLE FRAME MOUNTING FOR
BRASSIÈRES

Jack Glick, Bronx, N. Y., assignor to The Gluckin Corporation, New York, N. Y., a corporation of New York

Application May 22, 1946, Serial No. 671,424

3 Claims. (Cl. 2—42)

1

This invention relates to brassières employing reinforcing or supporting frames to aid in support of breasts by the pockets of the brassière. More particularly, the invention consists in providing edge portions of the breast pockets of a brassière or other garment with a frame mounting strip having means securing side portions of the strip together in forming thereof a channel for reception of parts of a frame in retaining the frame in the position on the breast pockets. Still more particularly, the invention deals with the use of what might be called a fastener strip comprising spaced fastener elements which may be arranged in pairs on the strip or with one element on the strip and the companion element upon the garment to which the strip is attached, thus providing a simple method of constructing the frame supporting channels on edge portions of the breast pockets of the garment. The novel features of the invention will be best understood from the following description when taken together with the accompanying drawing in which certain embodiments of the invention are disclosed, and in which the separate parts are designated by suitable reference characters in each of the views; and in which:

Fig. 1 is a front view of one breast pocket of a brassière showing one of my improved fastener strips attached thereto.

Fig. 2 is an inside view of the structure shown in Fig. 1, with the strip in completely assembled position.

Fig. 3 is a view similar to Fig. 2, showing the strip partially open and exposing the channel for attachment of the frame.

Fig. 4 is a section on the line 4—4 of Fig. 3; and

Fig. 5 is a plan view of a modified form of strip which I may employ.

In brassières employing supporting frames, it has been the common practice to either permanently attach and mount a frame in connection with the breast pockets of the garment or to provide on the garment means for detachably supporting the frame therewith, and in the latter instance, difficulty has been experienced in attaching and detaching the frame, particularly in threading the curved breast encircling loop portions of the frame through the garment parts.

The purpose of my invention is to provide a simple and practical means for providing a quick detachable mounting of the frame with respect to the garment and to employ a more or less standard form of fastener tape to accomplish the desired result with a suitable spacing of fastener elements on the tape adapting it to the intended

use. Still further my invention includes the use of a special and distinctly new type of fastener tape wherein pairs of fastener elements are employed on the tape with a definite relationship one with respect to the other in providing coupling engagement of said tapes. Here it is to be understood that other types and kinds of fastener elements can be employed than the snap fastener elements shown.

While my invention is applicable for use in conjunction with breast covering portions of garments of any type and kind, in illustrating one adaptation and use of my invention I have shown in the accompanying drawing the same applied to a brassière, and in illustration, the showing has been simplified in applying it to one pocket only of a brassière, the pocket is shown at 10 in the drawing and may be of any desired construction. As shown, a supporting and reinforcing frame 11 has its curved breast encircling loop portion 12 disposed at the lower and side portions of the brassière pocket. Attached to this lower and side edge portion is a fastener strip 13, which as seen in Figs. 1 to 4 inclusive, comprises a side portion 14 secured to the outer face of the pocket 10 with the inner side 15 of the strip disposed upon the inner surface of the pocket and having longitudinally spaced stud members 16 of snap fastener elements. The stud members 16 are adapted to engage correspondingly spaced socket members 17 secured to the inner surface of the pocket 10 in registering alignment with the stud members 16, as clearly seen in Fig. 3 of the drawing. The fold of the strip 13 is adapted to form a channel 18 longitudinally of the strip as clearly seen in Figs. 3 and 4 for reception of the loop 12 of the frame 11. The free end of the loop 12 has an inturned portion 19 to form a smooth terminal end, whereas the inner end portion of the loop 12 joins a companion loop, not shown, in a central bridging portion 20, comprising a spring loop 21 and shoulder portions 22—22'. On the loop 21 and shoulder portions 22—22' is disposed a protector sleeve 23 to protect the body from direct contact with the frame intermediate the pockets of the brassière. The upper inner portion of the pocket 10 includes a tie-ribbon or similar coupling 24 for joining adjacent upper portions of the pockets above the bridging portion 20.

In Fig. 5 of the drawing, I have shown a slight modification in the type of fastener strip employed. Here a strip 13' generally similar to the strip 13 is employed having side portions 14' and 15'. To the side portion 15' are attached stud parts 16' similar to 16 of Figs. 1 to 3, and at 17'

are shown socket parts secured to the side portion 14 rather than to the garment. With this construction, the side portion 14' is secured to the inner surface of the pocket, thus the strip 13 will be covered by the lower edge portion of the pocket, and in such uses, can be composed of an inexpensive undecorated material and other means can be employed to trim or finish the edge of the brassière pocket, as well known in the art.

The type of structure shown in Fig. 5 will lend itself to simplified attachment of fastener devices to the pockets in that the two fastener elements, namely the stud 16' and socket 17' can be attached to the one strip in the fabrication of this strip, thus dispensing with the need of alining the fastener 17 on the pocket so as to register with the fastener 16 on the strip.

With my improved construction, it will be apparent that a very quick and practical means is provided for attaching and detaching the reinforcing frames with a garment or the breast covering portions of a garment. It will also be understood that while I have shown a particular arrangement of the frame with respect to the garment, this may be modified and controlled by the shape of the frame and the positioning of the channel forming fastener strip on the garment.

Having fully described my invention, what I claim as new and desire to secure by Letters Patent is:

1. In garments having breast covering members with curved edges, means comprising a narrow fastener strip bordering said curved edges of each of said members, pairs of inter-engaging fastener elements spaced longitudinally of said strips and the bordering edges of said members, said fastener elements, when coupled, forming of the strips continuous channels longitudinally of said edges, a reinforcing frame having curved parts adapted to be arranged in the channels of said strips, and uncoupling of the fastener elements providing quick opening of the channels for detachment of the frame with respect to the garment.

5
10
15

2. In garments having breast covering members with curved edges, means comprising a narrow fastener strip bordering said curved edges of each of said members, pairs of inter-engaging fastener elements spaced longitudinally of said strips and the bordering edges of said members, said fastener elements, when coupled, forming of the strips continuous channels longitudinally of said edges, a reinforcing frame having curved parts adapted to be arranged in the channels of said strips, uncoupling of the fastener elements providing quick opening of the channels for detachment of the frame with respect to the garment, and the frame having a bridge portion joining said curved frame parts at channel ends.

3. A fastener strip of the character described comprising an elongated band having two narrow side portions, said side portions being integrally joined by an intermediate foldable portion arranging surfaces of said side portions adjacent, fastener elements spaced and secured longitudinally of one side portion, other and companion fastener elements spaced and secured longitudinally of the other side portion, and said fastener elements being arranged on said adjacent surfaces of the side portions to form a channel at the intermediate portion of the band when said elements of both side portions are coupled together.
